UNITED STATES PATENT OFFICE.

OLIVER E. MAYNARD, OF ARNOLD, PENNSYLVANIA, ASSIGNOR TO WINDOW GLASS MACHINE COMPANY, OF PITTSBURGH, PENNSYLVANIA, A CORPORATION OF NEW JERSEY.

GLASS-DRAWING APPARATUS.

1,114,896.

Specification of Letters Patent. Patented Oct. 27, 1914.

Application filed June 7, 1912. Serial No. 702,234.

To all whom it may concern:

Be it known that I, OLIVER E. MAYNARD, a resident of Arnold, in the county of Westmoreland and State of Pennsylvania, have invented an Improved Glass-Drawing Apparatus, of which the following is a full, clear, and exact description, reference being had to the accompanying drawings, forming part of this specification, in which—
10 Figure 1 is a side elevation showing one form of apparatus constructed in accordance with my invention, partly broken away. Fig. 2 is a detail end elevation of the drum. Fig. 3 is a partial top plan view, and Figs. 15 4, 5 and 6 are detail views on a larger scale, hereinafter referred to.

My invention relates to the automatic forming of the cap in the drawing of cylinders and is designed to improve upon the 20 apparatus shown and claimed in my pending application Serial No. 636,309, filed June 30th, 1911.

The general object of the present invention is to simplify, cheapen and improve 25 the apparatus for the automatic formation of the cap.

In the drawings, in which I show the invention as applied to the apparatus usually employed in drawing window glass cylinders, 2 represents an electric motor having its shaft provided with a worm which drives a worm wheel 3 on the shaft 4. To this shaft is fixed a pinion 5 intermeshing with toothed wheel 6 on the shaft 6^a which shaft 35 also carries a pinion intermeshing with toothed wheel 7 on the shaft 8 of the winding drum. On the drum 9 of shaft 8 winds the cable or flexible connection 10 by which the cage or elevator device carrying the 40 blow pipe or bait is carried. This drum 9 comprises a winding portion 11 of relatively smaller diameter and a tapered conical portion 12 of larger diameter, these parts being connected by a curved portion 13 of rapidly 45 increasing diameter. These parts are grooved in the usual manner to receive the cable, which is secured to the smaller drum portion. The smaller portion 11 and the portion 13 of rapidly increasing diameter 50 are used during the forming of the neck and cap, the cable winding on the gradually enlarging tapered portion 12 during the drawing of the cylinder proper. The object of this conical form for the main drum is to

slightly increase the speed during drawing 55 of the cylinder to compensate for the gradual cooling and stiffening of the glass.

In carrying out my invention, I provide a valve 14 in the air supply pipe 15 leading to the telescopic pipe system for the bait or 60 blow pipe. The lever fixed to the stem of this valve is connected preferably through insulation, shown at 17, to the portion 18 of a three-part rod or bar, the middle part 19 telescoping over 18 and being secured 65 when adjusted by set-screw 20, or in any other desirable manner. The portion 19 also adjusts over the third portion of the rod or bar and is similarly secured by set-screw, and this portion 21 of the bar carries on its 70 lower side a rack 22 which normally engages a pinion 23 on a short shaft 24 located below the drum shaft. The drum shaft is provided with a small pinion 25 intermeshing with toothed wheel 26 on the shaft 24 75 which carries the pinion 23, as shown in Fig. 4, thus driving the pinion shaft. Fixed to the shaft 24 is an arm 27, having adjustably secured in a slot thereof a laterally projecting lifting pin 28, which may or may not 80 have a loose roller or sleeve thereon. The pin 28 projects laterally so as to engage the recess 31 of a shifter block 29, which is adjustably secured to the rack 21 by set screw 30. 85

The arm will rotate in an anti-clockwise direction during lifting of the bait and at the proper time will engage the recess in the shifter block and lift the rack free from the pinion and carry it rapidly toward the left, 90 thus giving a rapid opening movement after the neck is formed. The latter portion of this movement is shown in Fig. 2. As the arm passes down to the left, the rack again comes into engagement with its pinion, thus 95 resuming the slow gradual opening of the valve. From this point on through the draw, the valve will be actuated solely by the rack and pinion connection as the pin 28 will not again come into engagement with 100 the recess of the shifter block until the bait is lowered for the next draw, when it will carry the block back to its original position. During the downward movement of the drawing cage or elevator, the winding 105 drum 9 and its gearing is rotated in the opposite direction, thereby moving the rigid bar in the reverse direction, a portion of

this movement being effected as in the reverse movement by means of the shifting block and arm.

In connection with the valve system shown, I preferably employ a counterweight 32, which is adjustably secured to an arm 33, fixed to the valve lever. This is merely to partially counterbalance the valve movements and make them easier.

10 In the use of the apparatus at the beginning of the draw, the valve 14 will be in its most nearly closed position slightly open. As the cable winds on the smaller portion 11 of the drum, the thick heavy glass neck portion of reduced diameter will be formed and during this movement the rack will be moved to the left in Fig. 1. At the proper moment, fixed by adjusting the parts, the pin 28 will engage the recess in the shifter block and lift the rack away from its pinion 25 and carry it over rapidly toward the left, as shown in Fig. 2. During this movement, the rack will be carried to the left a much greater distance than it would be carried by its pinion, and consequently, the valve will be suddenly and rapidly opened to swell out the glass to the size desired for the cylinder. Immediately after the cap is formed, the hoisting cable begins to wind on the intermediate portion 13, thus increasing the speed of draw to draw the glass thinner in the cylinder proper. From this time on, there is a slow gradual increase in the speed of draw, together with a slow gradual opening 30 of the air valve corresponding thereto, the rack and pinion having been brought into reengagement.

The advantages of my invention result from the simplicity, cheapness and effectiveness of the type of apparatus shown. The parts are reduced in number over the parts of my former apparatus, the apparatus is not as liable to get out of order, and the operation is positive and effective. As in my previous device, the need of skilled labor for forming the cap is done away with.

Many variations may be made in the form and arrangement of the valve-actuating connection, the means for imparting the rapid movement thereto to suddenly increase the air supply and form the cap, etc., without departing from my invention.

I claim:

1. Glass-drawing apparatus having means for separating the bait and glass receptacle during the drawing operation, an air supply having a controlling valve, and connections between the separating means and the said valve, said connections comprising a rigid movable member, and means for rapidly increasing the speed of movement of

said rigid member for a fixed predetermined period and for thereafter more slowly moving said rigid member; substantially as described.

65

2. In glass-drawing apparatus, an air valve, a rigid member connected to the valve, gearing for actuating said member, and supplemental mechanism arranged to increase the speed of movement of the rigid member through a predetermined period; substantially as described.

3. Glass-drawing apparatus, comprising lifting mechanism for the bait, an air supply, an air valve controlling said supply, a rigid rod or bar member connected to the valve and movable to open and close the same, connections from the lifting mechanism for effecting the movement of said rod or bar, and other mechanism operated through said connections arranged to act upon said connections to rapidly increase the speed of movement of the rod or bar through a predetermined period; substantially as described.

85

4. In glass-drawing apparatus, an air valve, a bar connected with the valve having a rack, gearing connected with the main hoisting drum and arranged to actuate the rack, and mechanism for disengaging the rack and gearing and moving the rack more rapidly through a predetermined period; substantially as described.

5. In glass-drawing apparatus, a lifting mechanism having a hoisting drum, an air supply, a valve controlling said supply, a rack connected to the valve, gearing for the hoisting drum engaging the rack, a connection between the rack and the valve, and an arm actuated by the said gearing and arranged to disengage the rack and gear through a predetermined period and then allow them to reengage each other, said arm also having an actuating connection with the rack; substantially as described.

105

6. Glass-drawing apparatus, comprising a lifting mechanism, an air supply, a control valve for the air supply, a rack connected to the valve, a gear engaging said rack and driven by the lifting mechanism, and a rotating member driven by said gear and arranged to effect the alternate engagement and disengagement of the rack and gear, said member also having an actuating connection with the rack; substantially as described.

110

In testimony whereof, I have hereunto set my hand.

OLIVER E. MAYNARD.
